(57) **CLAIM**

See application file for complete search history.

We claim the ornamental design for an adapter, as shown and described in the figures.

83/665		

FIG. 1 is a perspective view of an adapter embodying the invention, with the adaptor shown with a tool arbor for illustrative purposes.

FIG. 2 is a left side view of the adapter shown in FIG. 1.

FIG. 3 is a right side view of the adapter shown in FIG. 1.

FIG. 4 is a bottom view of the adapter shown in FIG. 1.

FIG. 5 is a top view of the adapter shown in FIG. 1.

FIG. 6 is a front view of the adapter shown in FIG. 1; and, FIG. 7 is a rear view of the adapter shown in FIG. 1.

The portions of FIG. 1 shown in broken lines are included for the purpose of illustrating environment and form no part of the claimed design.
